UNITED STATES PATENT OFFICE.

MAREA H. STOLL, OF BEATRICE, NEBRASKA.

COMBINED PUNCH AND BUTTON-SET TOOL.

1,272,870.

Specification of Letters Patent. Patented July 16, 1918.

Application filed November 20, 1917. Serial No. 202,976.

To all whom it may concern:

Be it known that I, MAREA H. STOLL, a citizen of the United States, residing at Beatrice, in the county of Gage and State 5 of Nebraska, have invented certain new and useful Improvements in Combined Punch and Button-Set Tools; and I do hereby declare the following to be a full, clear, and exact description of the invention, such as 10 will enable others skilled in the art to which it appertains to make and use the same.

This invention relates to a new and useful tool in the form of a combined punch and button set which is adapted to be used 15 to simultaneously punch and rivet or set a marker button through the ear of a hog or other animal.

A further object of the invention is to provide a tool of the above stated character 20 which is adapted to telescopically and rigidly connect the two parts of a marker button with a single operation.

A still further object of the invention is to provide each jaw of the tool with spring 25 tension means for holding each part of the button to its respective jaw prior to the actuation of the tool.

A still further object of the invention is to provide a simple and inexpensive tool 30 which is reliable and efficient in use.

With these and other objects in view as will appear as the description proceeds, the invention comprises the various novel features of construction, combination and arrangement of parts as will be fully described hereinafter and afterward specifically 35 claimed.

Referring to the drawings:

Figure 1 represents a fragmentary side 40 elevation of the tool showing the jaws arranged in open or inoperative position.

Fig. 2 represents a fragmentary vertical sectional view through the tool showing the jaws in closed or operative position, and 45

Fig. 3 represents a detail plan view of the forward portion of the lower jaw.

Similar characters of reference are used to denote corresponding parts throughout the accompanying drawings and the following 50 description.

In order that the construction and operation of the invention may be readily comprehended by those skilled in the art to which the invention relates, I have illustrated an approved embodiment thereof in

the accompanying drawings and will now proceed to fully describe the same in connection with said drawings, in which 1 and 2 indicate the handles of the tool which are pivoted adjacent their forward ends as at 3 60 in overlapping relation. Each handle is substantially U-shaped in cross section and has the back portion thereof cut away for a distance at the front end of the handle to receive the jaw bars 4 and 5. 65

Each jaw bar is substantially square in cross section and is pivoted adjacent its forward end as at 6 to its respective handle. The rear end of each jaw bar is provided with a longitudinally extending slot 7 70 through which is positioned a pin 8 rigidly attached to the adjacent handle. As shown the jaw bars are arranged in parallel planes and are adapted to be moved to and from each other in parallel planes by virtue of 75 their pivotal and sliding connections with the handles.

The jaw bar 4 is provided between its forward end and the pivot 6 with an aperture 9 formed adjacent one end with an enlargement of countersink 10, and said aperture and countersink are adapted to receive the base 11 and flange 12 of a piercing element. 13 indicates a pointed stud projecting axially from the base 11, and the inner 85 end of the stud is flared as indicated by the numeral 14 for a purpose which will presently appear.

The inner face of the jaw bar 4 is provided with a countersink 15 arranged concentrically of the piercing element and is adapted to receive the flange 16 of one telescopic part of a marker button, said flange being provided with a sleeve 17 adapted to be positioned over and in axial alinement 90 with the pointed stud 13.

18 indicates spring arms which are anchored in the jaw bar 4 at diametrically opposite points of the countersink 15 and have their outer ends bent inwardly toward each other for engagement with the flange 16 of said telescopic button part. The inner face of the jaw bar is cut away as at 19 to permit the outer ends of the spring arms to yield outwardly to enable the flange 16 to be positioned therebetween, the tension of said spring arms being sufficient to hold the flange against casual displacement. 100 105

The lower jaw bar 5 is provided at a point between its forward end and the pivot 6 110

with an aperture 20 for the reception of a tubular anvil 21, the outer end of which is of slightly larger diameter as indicated by the numeral 22 to provide an annular shoulder 5 for engagement with the inner surface of the jaw. The outer end of the tubular anvil is provided concentrically of its bore with a bead 23 adapted to be engaged within one end of the other telescopic part of the 10 button, as clearly shown in Fig. 2, and serves to hold the button part centered on the anvil in axial alignment with it and the first mentioned button part carried by the other jaw bar.

15 24 indicates a flat spring which has one end secured to the inner face of the jaw 5 by screws 25, and the other end is bifurcated as at 26 and is adapted to receive the sleeve 27 of the second telescopic button part. As 20 shown the outer end of the spring 24 is bowed outwardly and away from the jaw and extends over the end of the anvil 22 and is adapted to bear on the flange 28 of the second telescopic button part to hold it 25 on the anvil and in an operative position.

In the operation of the tool, the two telescopic parts of the marker button are attached to the respective jaws 4 and 5 in axial alignment with each other so that when the 30 handles are moved together, the jaw bars will also be moved together in parallel planes, thus causing the two parts of the button to telescope through each other. The pointed stud 13 by virtue of its relative position will 35 perforate the ear of the hog or other animal and facilitate the telescoping of the button parts through the ear perforation. At the same time that the button parts are telescoped through each other, the flared inner end 14 of 40 the stud 13 will serve to flare the outer end of the sleeve 27 and thus set or rivet it within the sleeve 17 of the other button part. From this construction it will be apparent that the tool will effectively act as a combined punch and button set, accomplishing 45 both with but a single operation.

After the button has been set or riveted through the ear of the animal, the handles of the tool are separated which will cause 50 the jaw bar 4 to recede from the jaw bar 5, the latter with the spring 24 holding the button so that the flange 16 may be readily disengaged from between the spring arms 18. The tool may be then moved laterally 55 and disengaged from the button.

Having thus described my invention, what I claim as new is:

1. A combined punch and button set tool comprising a pair of handles pivotally connected adjacent their forward ends in overlapping relation, a pair of jaw bars pivotally connected to the forward ends of said handles for movement to and from each other in parallel planes, an anvil carried by 65 one of said jaws, means for holding a tele-

scopic button part on said anvil, a piercing element carried by the other jaw bar, and means for holding the other telescopic button part on said jaw bar over and in axial alignment with said piercing element, said button parts adapted to be telescoped when 70 said jaw bars are moved together.

2. In a tool of the class described, the combination with a pair of jaw bars adapted to be moved to and from each other in parallel planes, an anvil carried by one of said jaw bars, a flat spring having one end attached to the jaw carrying said anvil and the other end bifurcated and bowed outwardly over said anvil, said bifurcation 75 adapted to receive the sleeve of one telescopic button part, said spring end adapted to bear on the flange of said button part and hold it on and in axial alignment with said anvil, a piercing element carried by the other 80 jaw bar and disposed in axial alignment with said anvil, and means for holding the other telescopic button part to said jaw bar over said piercing element.

3. In a tool of the class described, the combination with a pair of jaw bars arranged to move to and from each other in parallel planes, an anvil carried by one of said bars, spring tension means to hold one telescopic part of the marker button on said anvil, a 90 piercing element carried by the other jaw bar in axial alignment with said anvil, and having a swaging face at its base, the inner face of said last named jaw bar being formed with a countersink concentrically of 95 said piercing element and adapted to receive the flange of the other telescopic part of the marked button, and spring arms anchored in the jaw bar at diametrically opposite points of said countersink and adapted 100 to engage and hold the flange of the last named telescopic part of the button.

4. In a tool of the class described, the combination with a pair of jaw bars arranged to move in parallel planes, an anvil carried by one of said jaws, spring tension means to hold one telescopic part of the marker button on said anvil, a piercing element comprising a base mounted in the other jaw bar in axial alignment with said 110 anvil, a pointed stud extending axially from said base and having its inner end flared, said last named jaw bar formed with a countersink concentrically of said piercing element and adapted to receive the flange 115 of the other telescopic part of the marker button, and spring arms carried by said last named jaw bar at diametrically opposite points of said countersink and adapted to grip the flange of the telescopic button part 120 arranged therein, said inner flared end of the pointed stud serving to flare the outer end of the first mentioned button part when it has been telescoped through the last named button part to rigidly connect the button parts. 130

5. A combined punch and button set tool comprising a pair of handles, jaw bars mounted thereon to move in parallel planes, a tubular anvil carried by one of said jaw bars, means for retaining a tubular button part on said anvil, means for supporting a coöperating button part upon the opposite jaw bar, and a piercing element carried by said last mentioned jaw bar in alinement

with said anvil and provided with a swaging 10 face at its base.

In testimony whereof I have signed my name to the specification in the presence of two subscribing witnesses.

MAREA H. STOLL.
